UNITED STATES PATENT OFFICE.

EBBE S. KOLBECK, OF SAN DIEGO, CALIFORNIA.

LEAF-SPRING-ASSEMBLING MACHINE.

Application filed January 12, 1925. Serial No. 1,791.

My invention relates to a leaf spring assembling machine for springing the several leaves of a spring together so that they may be bolted together at their middle, and the objects of my invention are:

5 First, to provide a machine to facilitate the clamping of the several leaves of a leaf spring together preparatory to bolting them together at the middle in the usual manner.

10 Second, to provide a machine of this class whereby the spring leaves are clamped together without the leaves shifting end ways relatively to each other.

15 Third, to provide a machine of this class with means for shifting the operative structure whereby the clamping device may be moved into clamping position or away from clamping position as desired.

20 Fourth, to provide a spring clamping machine of this class whereby the clamping members are provided with a space at the middle thus providing for room for a mandrel for supporting the spring leaves in proper position while they are being clamped 25 into position.

25 Fifth, to provide a machine of this class whereby the springs may be clamped together flatwise, then after they are bolted the leaves may be aligned with each other 30 by turning the spring a one-quarter turn and then clamping the several leaves into alignment.

35 Sixth, to provide a novel spring clamping machine of this class, and—

35 Seventh, to provide a machine of this class which is very simple and economical of construction, durable, easy to operate and which will not readily deteriorate or get out of order.

40 With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

45 Figure 1 is a top or plan view of my machine showing a spring A ready to be clamped together thereon and omitting some of the operating parts; Fig. 2 is a similar view showing the spring in clamped position and 50 the spring bolt therein; Fig. 3 is a side elevational view of the machine on an en-

larged scale; Fig. 4 is a front elevational view thereof; Fig. 5 is a sectional view through 5—5 of Fig. 4, showing some of the parts broken away to facilitate the illustration and Fig. 6 is a sectional view through 6—6 of Fig. 4, shown on an enlarged scale.

55 Similar characters of reference refer to similar parts and portions throughout the several views of the drawings.

60 The moveable clamping plate 1, stationary clamping members 2 and 3, U shaped support 4, back frame member 5, side frame members 6 and 7, shaft 8, pinion 9, gear 10, gear rack 11, ratchet wheel 12, ratchet pawl 13, cam member 14, cam shaft 15, lever 16, main operating lever 17 and pawl 18 constitute the principal parts and portions of 65 my leaf spring assembling machine.

70 The side frame members 6 and 7 are rigidly secured together by means of the plate 5 at the back and beam 5^a at the front, the plate 1 is shiftable on the top of the frame formed by the members 5^a, 6 and 7 by means of a plate 1^a secured to the plate 1 at its 75 opposite sides and spaced from the plate 1; mounted on the upper edges of the members 6 and 7 are plates 6^a and 7^a which are preferably offset. Plates 1^a and 6^a and 7^a overlap and interlock with each other forming 80 the guide members for supporting the plate 1 relatively to the frame. Mounted in the middle on the lower side of the plate 1 is a gear rack 11 which is adapted to mesh 85 with the spur gear 10 which is mounted on a shaft 10^a, the shaft is journaled at its opposite ends in the frame members 6 and 7. Secured to back member 5 are the stationary 90 clamp members 2 and 3 which extend up over the plate member 1 and are secured together by means of the U member 4 thus providing 95 spaced apart stationary clamp members. Secured in the upper side of the plate 1 are a pair of spaced apart uprights 1^b and 1^c which form jaws or supports for engaging 100 the spring; meshing with the gear 10 is a pinion 9, which pinion 9 is mounted on a shaft 8 which extends from the side 6 to the side 7 and is journaled in said side members, the one end of this shaft 8 extends out 105 through the member 7 and some distance past said member. Rigidly mounted thereon is a ratchet wheel 12, and pivotally mounted on this extended end is the bifurcated end of the lever 17 which straddles said ratchet 110 wheel 12. Pivotally mounted between the bifurcated members of the lever 17 is a double

ratchet pawl 18 shown best in Fig. 6 of the drawings, which is provided with a boss 18^a thereon. Mounted in the lever is a spring 18^b supported by a spring 18^c which is adapted to hold the detent out against the pawl 18 on opposite sides of the boss 18^a for holding the opposite ends of the pawl in engagement with the ratchet wheel 12, the ratchet pawl 18 is provided with a handle 18^d to facilitate its movement. Mounted below the ratchet wheel 12 is another ratchet pawl 13 which is provided with a weight 13^a which counterbalances the same tending to hold the tooth end in an engagement with ratchet wheel 12, as shown in Figure 3 of the drawings. Positioned just below this weight in the frame 7 is a cam shaft 13 upon which is mounted a cam 14 which is adapted to raise the weight 13^a for shifting the pawl into and out of engagement with the ratchet wheel. Mounted on the shaft on the opposite side of the frame member 7 is a lever 16 for shifting the cam 14 into position for throwing the ratchet pawl into and out of engagement with the ratchet wheel 12.

The operation of my machine is as follows:

The spring A which is an ordinary leaf vehicle spring is provided with a mandrel B through the central holes of the spring, the whole is positioned between the bracket 4 and the uprights 1^b and 1^c on the moveable member 1; the pawl 18 is set with the member with the handle portion 8^b engaging the teeth of the ratchet wheel 12, as shown best in Figure 6 of the drawings, and the lever 17 drawn downwardly which turns the shaft which in turn turns the pinion 9 which turns the gear 10 and moves the rack 11 together with the member 1 and pulls uprights 1^b and 1^c toward the portion 4 clamping the spring members together, as shown best in Figure 2 of the drawings, after which a bolt is inserted in the central hole and the leaves secured together. As soon as the spring leaves are clamped together, as shown in Figure 2, the cam lever 16 is moved upwardly which causes the pawl 13 to engage the ratchet wheel which holds the ratchet wheel in such position. As soon as the spring is bolted together the lever is dropped down which releases the cam and the ratchet pawl is disengaged from the ratchet wheel 12, then the ratchet pawl 18 is shifted so that the member 18^b engages the other side of the boss 18^a of the cam member 18 so that the other end of the cam member 18 engages the ratchet wheel and by shifting the lever upwardly again the member 1 is positioned forwardly on the frame, then the spring can be turned a one-quarter turn and the same operation as before and the spring leaves positioned in alignment with each other after which the

spring clamp members are secured in position and the spring is ready for use.

Though I have shown and described a particular construction, combination and arrangement of parts and portions I do not wish to be limited to this particular construction, combination and arrangement but desire to include in the scope of my invention the construction, combination and arrangement substantially as set forth in the appended claims.

Having thus described my invention what I claim as new and desire to secure by Letters Patent is:

1. In a leaf spring assembling machine, a frame, a double stationary clamp member secured thereto, a moveable clamp member with double jaws shiftably mounted on said frame and lever, gear and ratchet means for shifting and holding said moveable clamp member. 80

2. In a leaf spring assembling machine, a frame, a double, U-shaped stationary clamp member extending over said frame, a moveable clamp member, comprising a platform for supporting the spring and having spaced jaws, shiftable relatively to said stationary member, positioned between the frame and said stationary member, a gear rack secured to the lower side of said moveable member, a gear meshing with said gear rack, a pinion meshing with said gear, a shaft upon which said pinion is mounted, a ratchet wheel secured on said shaft and ratchet and pawl means in engagement with said ratchet wheel 90 for holding said ratchet wheel in certain positions. 95

3. In a leaf spring assembling machine, a frame, a stationary clamp member extending over said frame, a moveable clamp member, shiftable relatively to said stationary member, positioned between the frame and said stationary member, a gear rack secured to the lower side of said moveable member, a gear meshing with said gear rack, a pinion 100 meshing with said gear, a shaft upon which said pinion is mounted, a ratchet wheel on said shaft and ratchet and pawl means in engagement with said ratchet wheel 105 for holding said ratchet wheel in certain positions and cam means for engaging and releasing one of said ratchet pawls. 110

4. In a leaf spring assembling machine, a double, U-shaped stationary clamp member, a moveable clamp member, comprising a platform for supporting the spring and having spaced jaws, shiftable relatively to said clamp member, a frame upon which said stationary member is secured and upon which said moveable clamp member is shiftably mounted, a pair of shafts mounted in said frame, a gear rack secured to said moveable clamp member, a gear on one of said shafts connecting with said gear rack, a pinion on the other shaft connecting with said gear, a 120

125

130

ratchet wheel secured to the shaft upon which the pinion is mounted, a lever loosely mounted on said shaft, a double ratchet pawl pivotally mounted on said lever and adapted 5 to engage said ratchet wheel in various shifted positions.

5. In a leaf spring assembling machine, a stationary clamp member, a moveable clamp member, shiftable relatively to said clamp 10 member, a frame upon which said stationary member is secured and upon which said moveable clamp member is shiftably mounted, a pair of shafts mounted in said frame, a gear rack secured to said moveable clamp 15 member, a gear on one of said shafts connecting with said gear rack, a pinion on

the other shaft connecting with said gear, a ratchet wheel secured to the shaft upon which the pinion is mounted, a lever loosely mounted on said shaft, a double 20 ratchet pawl pivotally mounted on said lever and adapted to engage said ratchet wheel in various shifted positions, another ratchet pawl adapted to engage said ratchet wheel provided with a counterbalance 25 weight, a cam shaft means for shifting said ratchet pawl into and out of engagement with said ratchet wheel.

In testimony whereof, I have hereunto set my hand at San Diego, California this 3rd 30 day of January, 1925.

EBBE S. KOLBECK.
